UNITED STATES PATENT OFFICE.

ARTHUR SKEFFINGTON, OF BLACKHEATH, LONDON, ENGLAND.

APPARATUS FOR HANDLING INVALIDS OR THE LIKE.

1,082,177.

Specification of Letters Patent.

Patented Dec. 23, 1913.

Application filed July 15, 1911. Serial No. 638,743.

To all whom it may concern:

Be it known that I, ARTHUR SKEFFINGTON, a subject of the King of England, residing at Blackheath, London, England, have invented certain new and useful Improvements in Apparatus for Handling Invalids or the like, of which the following is a specification.

This invention is for improvements in or 10 relating to invalid apparatus of the type that comprises a roller carried by mounts secured on the end-frame at the head of the bed and receiving a long-sheet that hung freely from the roller. A second 15 roller could be similarly mounted on the end-frame at the foot of the bed, if desired, and by connecting the sheet to both rollers and winding it up the patient could be lifted from the bed.

20 Where the bedstead is not too light, the above arrangement is found quite satisfactory, but with light bedsteads the longitudinal members of the bed or the end frames themselves, are liable to buckle under the 25 strain put upon them. Previously it has been proposed to employ upright supports or end frames that carry lifting pulleys and that rest direct on the floor.

According to the present invention, there 30 are combined with one or more lifting rollers or the like and upright supports or end frames therefor, side wings or struts for the supports, the supports or their struts or both being arranged when loaded to rest direct 35 upon the floor.

In some cases the side wings may be extended to meet each other so that the whole apparatus is self-supporting.

In the accompanying drawings:—Figure 40 1 is a perspective view of a self-supporting form of the apparatus constructed according to this invention erected around a bedstead; Fig. 2 shows the same apparatus with the bedstead removed; Fig. 3 is a perspective view of a modified form of the apparatus according to this invention; Fig. 45 4 shows a detail of Fig. 3 on a larger scale; Fig. 5 is a section of Fig. 4 on the line 5—5, and Fig. 6 is a perspective view showing yet 50 another construction according to this invention.

Like letters indicate like parts throughout the drawings.

The roller supports or end-frames M⁶ are 55 built of vertical members A connected to

gether by transverse members A¹. The rollers B carried by the end-frames may be connected by any convenient means to the vertical elements of the frame, such means preferably being adjustable so that the rollers 60 can be situated at different heights according to the purpose for which they are required.

Pivoted to each vertical member of the end-frames is a side wing comprising two 65 horizontal rods C connected by vertical rods C¹ and a strut C² that extends from the upper portion of the member A down to the upper horizontal member C. The rods or tubular elements C are hinged or pivoted 70 to the elements A by tubular T-pieces C³ that are free on the members A and are rigidly secured to the elements C. The T-pieces are prevented from endwise movement on the members A by suitable stops. 75 The struts C² may be adjustably connected to the elements A and C, or the eye C⁴ on the element A that receives the upper end of the strut may be made to pivot about the strut, in which case stops may be provided to prevent it from moving along the vertical member.

The end-frames A, A¹ are made wide 80 enough to extend beyond the end-frames D of the bed with which they are to be used and the wings C¹, C², are made of sufficient length to meet or approximately meet when placed in the position shown in Figs. 1 and 2. The two end members C¹ of each pair of wings can then be secured together by 85 straps or any other fastening E. The apparatus can thus be quickly erected around any bedstead, one piece of apparatus serving perhaps the whole ward of a hospital, and the wings being hinged to the end frames 90 enables the apparatus to be more readily stowed away or conveyed from place to place. The end-frames may be carried on wheels F. Thus by tilting any one end-frame backward so that the wings clear the 95 floor, this half portion of the apparatus can be wheeled from one place to another.

It will be seen that this apparatus as a 100 whole constitutes a collapsible and self-supporting lifting frame that is, it does not in any way depend on the bed for support and may be used without a bedstead as shown in Fig. 2.

The rollers B may be used to operate a drawsheet G or to lift a frame G¹ as shown, 110

or they may be applied to any other purpose to which the apparatus is adapted.

In some cases the side wings may take a very simple form such as is shown in Fig. 3 where they constitute merely struts H adjustable at H^1 on the vertical members of the roller supports. The struts are provided with an adjustable clamp for connecting them to the longitudinal members J of the bedstead. The clamp comprises a yoke K that can slide upon the strut H , Figs. 4 and 5, and is secured by set screws K^1 . The yoke K thus provides a slot K^2 between it and the strut H , and through this a bolt L extends. The bolt has a hooked end L^1 that is engaged with the member J of the bedstead and the other end of the bolt receives a winged nut L^2 . Between the nut and the strut H with its yoke K , a plate L^3 is interposed and it will thus be seen that a certain amount of adjustment is permitted the strut H without shifting the yoke K and further adjustment may be obtained by releasing the set screw K^1 and moving the yoke along; the connection H^1 can also be moved along the roller support as already mentioned. The adjustment of these struts is preferably such that their lower ends are nearly but not quite in contact with the floor so that when loaded the give of the bedstead lowers them against the floor thereby preventing further distortion of the bedstead. The roller supports M^* used with this construction of strut may extend down to the floor if desired, but those shown in Fig. 3 are provided with transverse frame members M^1 , that rest upon the bedstead to take the downward thrust and they are retained in a vertical position by straps or other fastenings M^2 M^3 connecting them to the end-frames of the bedstead itself. The vertical members of the roller support at the end where the fastenings M^3 are located are conveniently carried down below the level of the longitudinal members J of the bedstead as shown at M^4 . These downward extensions M^4 thus help the struts H to resist the pivoting tendency of the roller support about the fastenings M^3 .

In the construction described in Fig. 3 the bedstead itself completes the supporting structure for the rollers, as whether the roller supports are extended down to the ground or not the bedstead constitutes the distance pieces between the two end supports preventing them from being drawn together. Instead, however, of the bedstead serving this purpose, the roller supports may themselves be provided with longitudinal distance members N , Fig. 6. These members may be dropped into chills N^1 secured to the vertical members of the supports and operating in the same manner as the chills for receiving the longitudinal members of the bedstead. The struts O may

be connected to the longitudinal members N by a clamp such as is shown in Figs. 3, 4 and 5 or by other suitable means.

The apparatus shown in all the figures of the accompanying drawings is conveniently made up of tubing, but this as will be readily understood, is not essential to the invention.

Obviously, the struts H and O need not be formed in one piece, for instance, the upper portion of the strut O could be clamped to the longitudinal member N and the lower portion, which might be separate from it, could also be clamped to the longitudinal member N either in a position directly opposite the portion O or at a distance therefrom. For example, the two lower portions of the struts O on one side of the apparatus could be situated in the position shown at O^* in dotted lines, Fig. 6, and hinged together at O^1 , the free ends of the members O^* being adjustably connected to the longitudinal member N . Obviously, this arrangement could be applied to apparatus wherein the bedstead forms one of the supporting elements.

In the self-supporting apparatus where the wings of one roller-support meet those of the other, the wings may be extensible either by making them telescopic or otherwise adjustable; they may moreover be connected together only at their bases as will be readily understood.

What I claim as my invention and desire to secure by Letters Patent is:—

1. In an apparatus of the character described, the combination of a vertical head-frame, a vertical foot-frame, a transverse roller on the head-frame, a sheet having one end wound on the roller, a transverse roller on the foot-frame receiving the opposite end of the sheet that is wound on the head-frame roller, means for anchoring the two frames so that one cannot travel bodily toward the other under the pull of the sheet upon the two rollers, struts on the head-frame extending downward at each side for direct contact with the floor and forward toward the foot-frame, and struts on the foot-frame extending downward at each side for direct contact with the floor and forward toward the head-frame, substantially as set forth.

2. In an apparatus of the character described, the combination of a vertical head-frame, a vertical foot-frame, a transverse roller on the head-frame, a sheet having one end wound on to the roller, a transverse roller on the foot-frame receiving the opposite end of the sheet that is wound on the head-frame roller, means for anchoring the two frames so that one cannot travel bodily toward the other under the pull of said sheet, struts hinged to the head frame about vertical axes, and struts hinged to the

- foot-frame about vertical axes extending downward for direct contact with the floor and forward toward the other frame, substantially as and for the purpose set forth.
- 5 3. In an apparatus of the character described, the combination of a vertical head-frame, a vertical foot-frame, a transverse roller on the head-frame, a sheet having one end wound on to the roller, a transverse roller on the foot-frame receiving the opposite end of the sheet that is wound on the head-frame roller, means for anchoring the two frames so that one cannot travel bodily toward the other under the pull of the 10 sheet upon the two rollers, struts in the form of side frames that are hinged about vertical axes to the head-frame and extend downward at each side for direct contact with the floor and forward toward the foot-frame, struts in the form of side frames hinged to the foot-frame and extending downward at each side for direct contact with the floor and forward where they meet the ends of the side-frames of the head-frame, and means for connecting the side-frames of the head-frame to the side-frames of the foot-frame, substantially as 15 set forth.
4. In an apparatus of the character described, the combination of a vertical head-frame that is supported direct from the floor, a vertical foot-frame that is supported direct from the floor, a roller on the head-frame disposed transversely, a sheet 20 wound on to the roller, a roller on the foot-frame disposed transversely receiving the opposite end of the sheet that is wound on the head-frame roller, side frames hinged about vertical axes to the head-frame and 25 extending forward and downward for direct contact with the floor, side frames hinged about vertical axes to the foot-frame and extending downward for direct contact with the floor, and means for preventing the side 30 frames from splaying laterally substantially as set forth.
5. In an apparatus of the character described, the combination of a vertical head-frame that is supported direct from the floor, a vertical foot-frame that is supported direct from the floor, a roller on the head-frame disposed transversely, a sheet wound on the roller, a roller on the foot-frame disposed transversely, and the opposite end of the sheet that is wound on the head-frame roller, side struts hinged about vertical axes to the head-frame and side struts hinged about vertical axes to the foot-frame, said struts extending forward and downward for direct contact with the floor, and comprising an upper diagonal member and a lower horizontal member with a downwardly directed extension, the diagonal member being hinged at its top to the head-frame and rigidly connected at its bottom to the horizontal member, which horizontal member is also hinged to the head-frame, about vertical axes and extending downward at each side for direct contact with the floor and forward to the head-frame, each strut comprising a diagonal member and a horizontal member having a downwardly directed extension, the diagonal member being hinged at its upper end to the foot-frame and rigidly secured at its lower end to the horizontal member which lower end is also hinged to the foot-frame, and means for preventing splaying of the struts laterally, substantially as and for the purpose set forth.
- 35 80
- In testimony whereof I have signed my name to this specification in the presence of two subscribing witnesses.

ARTHUR SKEFFINGTON.
